UNITED STATES PATENT OFFICE.

WALTER J. DREW, OF GRAND RAPIDS, MICHIGAN, ASSIGNOR TO THE BISSELL
CARPET SWEeper COMPANY, OF SAME PLACE.

CARPET-SWEeper.

SPECIFICATION forming part of Letters Patent No. 426,116, dated April 22, 1890.

Application filed May 13, 1889. Serial No. 310,516. (No model.)

To all whom it may concern:

Be it known that I, WALTER J. DREW, a citizen of the United States, residing at Grand Rapids, in the county of Kent and State of Michigan, have invented new and useful Improvements in Carpet-Sweepers, of which the following is a specification.

My invention relates to carpet-sweepers, and the purpose thereof is to provide an apparatus which may not only be operative for the ordinary uses to which a sweeper is adapted, but which is especially adapted to pick up objects of more than ordinary size or weight, which cannot readily be swept directly into the pan, thereby rendering the sweeper useful upon the floors of hotels, offices, public buildings, and other places where the litter accumulating comprises a great variety of objects of all sizes and where the floors are frequently without covering.

It is a further purpose of my invention to provide simple means for the simultaneous adjustment toward or from the floor of the double brush composed of two independent and oppositely-revolving brushes, and to combine therewith suitable mechanism for imparting the required movement thereto.

To these ends the invention consists in the arrangement within a casing of two rollers contiguous or in close proximity to each other, those parts of said rollers next to the floor or carpet revolving toward each other for the purpose of picking up litter by carrying it between said rollers instead of sweeping it directly into a pan between the brushes, as is usual.

The invention also consists in the combination, with a casing and two brushes arranged in juxtaposition, of pans arranged outside said brushes and mechanism for revolving the brushes so that their lower portions move toward each other.

In the accompanying drawings, Figure 1 is a top plan view of a sweeper embodying my invention. Fig. 2 is an end elevation of the same. Fig. 3 is a vertical transverse section taken near one end in the line 3 3 of Fig. 1. Fig. 4 is a detail view of one of the journal-supporting brackets removed from the

In the said drawings, the reference-numeral 1 denotes the sweeper-casing, which may be of any suitable form and construction, within which are arranged two similar brush-rollers 2, placed in actual contact with or in close proximity to each other. As one convenient method of mounting these brush-rollers, I have shown them provided with prolongations 3 upon each end, said prolongations lying in vertical slots 4 in the end walls of the 55 casing. Journal-pins 5 are set in the ends of these prolongations, and have their bearing in brackets 6, each bracket having an arm 7, which is laid against the end wall of the casing and pivotally mounted upon the shaft or 60 bearing 8 of one of the driving-wheels. A keeper 10 surrounds this arm 7 and permits its rise and fall while retaining it against outward displacement. Both brush-rollers being journaled in the brush-arm 6, the vibration of the latter upon its pivotal point 70 will give simultaneous vertical adjustment to both.

At each end of the casing I mount a driving and supporting wheel 12, preferably upon 75 the pivotal support or bearing 8 of the brackets. These wheels are of such diameter as to permit the attachment of pulleys 13, which receive belts 14, which are carried over pulleys 15 on the shaft of one brush-roller, thence 80 back around similar pulleys 16 on the shaft of the other roller, thence over idlers 17, and back to the driving-pulleys. The idler-pulleys are each mounted on a bearing 18, which is carried through a slot 19 in the end of the 85 casing and bent parallel with the wall, its end being turned toward the side opposite the driving-pulley and connected to a spring 20, by which the pulley is constantly drawn away from the driving-pulley to tighten the belt. 90 The arrangement is the same at each end of the casing, supporting-wheels 21 being arranged at such points as to act in conjunction with the driving and supporting wheels 12 in carrying the sweeper.

Upon each side of the casing outside the brushes is mounted a dust-pan 22, turning upon pivotal bearings 23, and having any suitable form of catch or fastening 24, to retain the pan in a closed position. The construction 95 100

and arrangement of these pans need not differ essentially from those in the ordinary form of sweeper.

The sweeper is propelled by a handle 25, 5 attached to the casing in any desired manner.

In using the apparatus it is intended that the direction of motion shall be such that the brush-rollers, which always turn in opposite directions, shall have their lower portions which 10 are in contact with the floor or carpet moving toward each other. In this manner the rubbish upon the floor is picked up between the bristles of the contiguous or adjacent brushes, carried up between them, and then over 15 into the pans, instead of being swept directly into the pans, as usual. By this operation large and more than ordinarily heavy substances are taken up with ease, whereas the sweepers heretofore used would be unable to 20 accomplish such a result or would effect it imperfectly.

It is evident that the mechanism for driving the brush-rollers may be very widely varied, as also may be the devices wherein the 25 rollers are journaled. I do not, therefore,

limit myself to any special form of such devices, my invention consisting, broadly, in the employment of two oppositely-revolving contiguous brushes, and in means for giving a simultaneous vertical adjustment thereto. 30

What I claim is—

1. In a carpet-sweeper, the combination, with a casing, of two brushes supported in such juxtaposition that they co-operate to pick up and carry particles, and mechanism 35 for revolving the brushes so that their lower portions move toward each other, substantially as described.

2. In a carpet-sweeper, the combination, with a casing and two brushes arranged in 40 juxtaposition, of pans arranged outside said brushes and mechanism for revolving the brushes so that their lower portions move toward each other, substantially as described.

In testimony whereof I affix my signature 45 in presence of two witnesses.

WALTER J. DREW.
